CLAIM

The ornamental design for a garment cart, as shown and described.

DESCRIPTION

FIG. 1 is a front isometric view of our new design for a garment cart.

FIG. 2 is a left side elevation view of FIG. 1.

FIG. 3 is a back side elevation view of FIG. 1.

FIG. 4 is a top plan view of FIG. 1.

FIG. 5 is a right side elevation view of FIG. 1.

FIG. 6 is a front side elevation view of FIG. 1.

FIG. 7 is a bottom plan view of FIG. 1.

FIG. 8 is a back isometric view of FIG. 1.

FIG. 9 is a front isometric view of a second embodiment of our new design for a garment cart.

FIG. 10 is a left side elevation view of FIG. 9.

FIG. 11 is a back side elevation view of FIG. 9.

FIG. 12 is a top plan view of FIG. 9.

FIG. 13 is a right side elevation view of FIG. 9.

FIG. 14 is a front side elevation view of FIG. 9.

FIG. 15 is a bottom plan view of FIG. 9; and,

FIG. 16 is a back isometric view of FIG. 9.

The features shown in light grey in the drawing depict portions of the garment cart that form no part of the claimed design

1 Claim, 16 Drawing Sheets
